UNITED STATES PATENT OFFICE.

FRANK A. HALLECK, OF CHICAGO, ILLINOIS, ASSIGNOR TO SULLIVAN MACHINERY COMPANY, A CORPORATION OF MASSACHUSETTS.

FORGING MECHANISM.

Application filed April 5, 1922. Serial No. 549,897.

My invention relates to forging mechanisms, and more particularly to gaging mechanisms for imparting to rock drill steels accurate gage and a particular conformation at their forward ends which has been found most desirable in practice.

An object of my invention is to provide an improved forging mechanism. Another object of my invention is to provide an improved gaging die mechanism. A further object of my invention is to provide an improved gaging mechanism for use in the sharpening of drill steels. A still further object of my invention is to provide an improved hammer gaging mechanism for accurately imparting to the forward end of drill steels a special conformation and an accurate gage. A still further object of my invention is to provide improved gaging mechanism having improved means associated therewith for insuring the formation of bits of accurate gage. Other objects and advantages of my invention will hereinafter more fully appear.

In the accompanying drawings I have shown for purposes of illustration one form which my invention may assume in practice.

In these drawings,—

Fig. 1 is a front elevation of a pair of dies and the adjusting stop member constituting the illustrative form of my invention, a fragment being broken away to show a detail of construction.

Fig. 2 is a section on the line 2—2 of Fig. 1.

Fig. 3 is a section on the line 3—3 of Fig. 1, with parts shown in different positions.

Fig. 4 is a front elevation of the stop member removed from its operative position.

Fig. 5 is a section taken on the line 5—5 of Fig. 4.

It is a well known fact that rock drill bits are usually sharpened by a hammering process combined with a dollying process. For the purpose of forming the wings of the bits, swaging dies illustrated herein at 1 and 2 are commonly used, these dies being provided with swaging surfaces 3 and 4 re-

spectively, and grooves 5 and 6 to receive the more or less finished wings. These dies 1 and 2 are ordinarily mounted in a drill sharpener with the die 2 secured in an anvil block while the die 1 is either positively reciprocated or hammered while in engagement with a heated drill steel by well known pneumatic motor mechanism. In view of the great importance which has been discovered to lie in the accurate formation of drill bits to provide them with what are known as reaming edges, that is, edges at the ends of the wings which shall lie within a cylindrical surface whose diameter is equal to the gage of the drill bit, and in view of the great importance, if power and time are to be saved, of securing accurate differences in gage between successive steels to be used in drilling, it is desirable to provide accurate means for forming true reaming edges on drill steels and to permit without excessive consumption of time the accurate gaging of the steels.

For the purpose of simply accomplishing these desirable results I provide, herein upon the dies 1 and 2, gaging surfaces 9 and 10, which surfaces will be noted to be of flatter transverse curvature at their forward ends than at their rearward ends, the forward ends being indicated at 11 and the rearward ends at 12. It will further be noted from observation of Fig. 1 that the curvature at the ends of the gaging surfaces is flatter than, or lies outside of, circles corresponding to minimum and maximum gages of steels which may be worked therein, these circles being marked A and B and the former coinciding with the outline of the stop hereinafter referred to. As a result of this construction, it will be found possible to form bits which have reaming edges lying in cylindrical surfaces corresponding to the gages of the different bits and, as at the extremes of the surfaces 9 and 10, the curvatures are flatter than the maximum and minimum gages, obviously at intermediate points the same condition will prevail.

Now for the purpose of locating a bit accurately at different points along the space between die surfaces 9 and 10 I provide a

stop member 13 having a laterally projecting neck 14 from which depends an arm 15 to which a nut, herein square in outline, is shown attached at 16. This nut is guided 5 in a generally rectangular channel 17 formed herein in a block 18 fastened to the side of the die 2 and a screw 19, fixed against longitudinal movement as at 20 and having a rotating handle 21, cooperating with the 10 threaded portion 22 of the member 16 to permit forward and backward movement of the stop member 13 between the dies. The forward face of the stop member is provided with recesses of the correct contour to 15 receive the sharpened ends of drill bits, these grooves being designated 23. Since the stop member is supported with its center midway between the dies when the latter are in their most proximate positions, it will 20 be evident that the stop will accurately receive and support any gage of drill bit.

From the foregoing description the mode 25 of operation of this device will be readily apparent. When it is desired to gage a small bit, the stop will be adjusted to a position nearly corresponding to that shown in Fig. 2. To gage a medium sized bit the stop will be moved to a position as shown in Fig. 3, while to gage a large sized bit 30 the stop will be moved still further to the right in Fig. 3. It will be noted that the taper of the die surfaces 9 and 10 is flatter than the original taper of the forward end of the drill bit and accordingly but relatively little metal needs to be displaced to accurately gage the drill bits, and the forward ends of the drill bits are given a flatter curvature than the supporting portions of the conical ends of the bits by means of my 35 improved gaging die. It will be obvious that, if desired, any suitable form of index may be employed with the screw and nut mechanism, as, for example, by the placing of graduations upon the top of the member 18 which supports and guides the block 16, or by arranging suitable indexes to be driven by rotation of the crank 21. As these 40 various means will be readily understood from the description, no illustration is provided. While I have in this application specifically 45 described one form which my invention may assume in practice, it will be understood that this form of the same is shown for purposes of illustration and that the invention may be modified and embodied in various other forms without departing from its spirit or the scope of the appended 50 claims.

What I claim as new and desire to secure 55 by Letters Patent is:

1. Gaging mechanism comprising co-operating oppositely disposed dies each having a gaging groove therein of curved section and of flatter transverse curvature at one 60 end than at the other, stationary support-

ing means for one of said dies, means for reciprocating the other of said dies, a stop member movable between said dies, and a support for said stop member including a block secured thereto and a guide for said 70 block secured to the side of one of said dies.

2. Gaging mechanism comprising cooperating oppositely disposed dies each having a gaging groove therein of curved section and of flatter transverse curvature at one end 75 than at the other, stationary supporting means for one of said dies, means for reciprocating the other of said dies, an adjustable stop member disposed between said dies, and a support for said stop member including a block secured thereto and a member having a block guiding channel formed therein secured to the stationary one of said dies with the open side of said channel directed towards the same. 80

3. Gaging mechanism comprising cooperating dies having oppositely disposed gaging grooves formed therein, said grooves being of curved section and of flatter transverse curvature at one end than at the other, stationary supporting means for one of said dies, means for reciprocating the other of said dies, an adjustable stop member disposed between said dies, a support for said stop member including a block secured thereto and a member having a block guiding channel formed therein and secured to one of said dies, and means for adjusting said stop member including an adjustable screw and nut connection between the same 90 and said member. 100

4. Gaging mechanism comprising cooperating dies having oppositely disposed gaging grooves formed therein, said grooves being of curved section and of flatter transverse curvature at one end than at the other and of flatter transverse curvature at any point than the arc of a circle whose diameter is equal to the gage of a bit to be gaged at that point, stationary supporting means for one of said dies, means for reciprocating the other of said dies, an adjustable stop member disposed between said dies, a support for said stop member including a block secured thereto and a member having a block guiding channel formed therein and secured to one of said dies, and means for adjusting said stop member including threads formed in said block and a rotatably mounted screw supported in said member. 110 120

5. Gaging mechanism comprising cooperating dies having oppositely disposed gaging grooves formed therein, said grooves being of curved section and of flatter transverse curvature at one end than at the other, stationary supporting means for one of said dies, means for reciprocating the other of said dies, an adjustable stop member having grooves formed in the rearwardly directed face thereof to receive the extremities of the 125 130

wings of a drill steel to be gaged thereby disposed between said dies, a support for said stop member including a block secured thereto and a member having a block guiding channel formed thereon and secured to one of said dies, and means for adjusting said stop member including threads formed in said block and a rotatably mounted screw supported in said member.

10 6. Gaging mechanism comprising cooperating oppositely disposed dies each having a gaging groove therein of curved section and of flatter transverse curvature at one end than at the other, stationary supporting means for one of said dies, means for reciprocating the other of said dies, a stop member movable between said dies, and screw and nut means for adjusting said stop member disposed along a longitudinal side 15 of said dies.

20 7. Gaging mechanism comprising cooperating oppositely disposed dies each having a gaging groove therein of curved section and of flatter transverse curvature at one end than at the other, stationary supporting means for one of said dies, means for reciprocating the other of said dies, a stop member movable between said dies, and means for adjusting said stop member including a nut connected thereto and a stationary screw disposed at one longitudinal side of and adjustable from in front of said dies.

25 8. Gaging mechanism comprising cooperating oppositely disposed dies each having a gaging groove therein of curved section and of flatter transverse curvature at one end than at the other, stationary supporting means for one of said dies, means for reciprocating the other of said dies, a stop member movable between said dies, and means for adjusting said stop member including a plurality of movable adjusting means disposed along one longitudinal side 40 of said dies, one of said movable means being rigidly connected to said stop.

30 9. Gaging mechanism comprising cooperating dies having relatively longitudinally fixed gaging surfaces, stop means for a steel 50 associated with said dies and movable relative to said surfaces, and means for adjusting said stop means disposed entirely at one longitudinal side of said dies.

35 10. Gaging mechanism comprising cooperating gaging dies, stop means for a steel associated therewith, and means for adjusting said stop means including a plurality of 55 adjusting members movable along a longitudinal side of said dies while maintaining an operative relation to said mechanism.

40 11. Gaging mechanism comprising cooperating dies having a gaging groove, said dies having an opening disposed along the side 60 of the same and in communication with said groove when said dies are in contact, stop

means disposed in said groove and having a portion projecting laterally through said opening, and means for supporting said portion disposed entirely at one side of said dies.

70 12. Gaging mechanism comprising cooperating dies having a gaging groove associated therewith and provided with relatively longitudinally fixed gaging surfaces, adjustable stop means disposed within said groove, 75 means disposed only at one longitudinal side of said dies for supporting said stop means, and actuating means for said stop means including a movable member disposed along said side.

80 13. Gaging mechanism comprising cooperating dies having a gaging groove associated therewith and provided with relatively longitudinally fixed gaging surfaces, adjustable stop means disposed therein, a member rigidly fixed to said stop, and rotatable means cooperating with said member and adapted upon rotation to adjust said stop means.

85 14. Gaging mechanism comprising cooperating dies having a gaging groove associated therewith, adjustable stop means disposed therein, means providing a guiding groove and a guided member therein for supporting said stop means, and means for 90 adjusting said latter means including rotatable and reciprocable members one of which has a portion disposed within said groove.

95 15. Gaging mechanism comprising cooperating gaging dies having an opening in the side thereof, stop means associated with said dies including an arm extending through said opening and carrying a nut, and a screw for said nut for adjusting said 100 stop means.

105 16. Gaging mechanism comprising cooperating gaging dies having an opening in the side thereof, stop means associated with said dies including an arm extending through said opening and carrying a nut, and a screw therefor disposed substantially 110 parallel to the longitudinal axis of said dies.

115 17. An article of manufacture for gaging mechanism comprising a single steel positioning abutment element having a portion adapted to engage a steel and another portion having an opening extending parallel to the longitudinal axis of said steel engaging portion adapted to cooperate with relatively movable actuating means the movement of which imparts movement to said element.

120 18. Gaging mechanism comprising cooperating relatively longitudinally fixed gaging dies, adjustable stop means associated therewith, and means for supporting and holding said stop means in any adjusted position thereof disposed along the side of said dies, said means including an element 125 130

disposed along said side and over which said stop means is movable.

19. Gaging mechanism comprising cooperating relatively longitudinally fixed gaging dies, adjustable stop means associated therewith, and means for supporting and holding said stop means in any adjusted po-

sition thereof disposed along the side of said dies, said means including an apertured arm and a shaft extending therethrough along 10 which said stop means moves.

In testimony whereof I affix my signature.

FRANK A. HALLECK.
